AUTOMATIC ALARM

Filed Aug. 12, 1931

FIG 1

FIG 2

INVENTOR
ALBERT KOENIG

BY
H. S. Hodges
ATTORNEY

UNITED STATES PATENT OFFICE

ALBERT KOENIG, OF NEWARK, NEW JERSEY

AUTOMATIC ALARM

Application filed August 12, 1931. Serial No. 556,690.

This invention is an automatic device for sounding an alarm in the event of a fire, or other emergency, which creates an increase of temperature in the locality or space to be protected.

One of the objects of the invention is to provide a thermally controlled alarm device, which will remain inoperative under normal temperature conditions in a room or other space in which the alarm is located, but which will be automatically set in operation upon an increase of temperature within said space, beyond a predetermined maximum. A further object is to provide an alarm device with means for normally preventing its operation, and thermally controlled means for promptly releasing said alarm device from said operation-preventing means in case of fire. A further object is to provide an alarm mechanism which is equipped with a trip arm which controls its operation, with mechanism for normally preventing movement of said arm, and a movably mounted thermal element, which is capable of automatic movement when the temperature rises to a predetermined maximum in its vicinity, to trip the arm, so that the alarm mechanism is set in operation.

The invention will be hereinafter fully set forth and particularly pointed out in the claims.

In the accompanying drawing:—

Figure 1 is a front elevation of an alarm device constructed in accordance with the invention, parts being broken away and other parts shown in section. Figure 2 is an edge view, parts being broken away and other parts shown in section.

Referring to the drawing, 10 designates a base of any suitable shape or material, having a gong 11 mounted thereon. Suitably secured to said base is the spring actuated alarm-operating-train A of a standard type alarm clock, the same being conventionally illustrated in the drawing, with the striker 12 positioned adjacent to the gong 11. The operation of the alarm mechanism is controlled by a standard character trip arm 13, of the type which is normally held in a position to lock the alarm train against move-

ment, and is periodically released in a manner well known in the art of horology, and which need not here be repeated. It is to be understood, however, that no other part of a clock mechanism is employed here.

Pivotedly mounted on the base 10 is an alarm-control lever L, provided with an arm 14 positioned to engage the trip arm 13, so as to hold it in a position to lock the alarm train A. Said lever is also formed with a longer arm 15 which is provided with a lug 16 on its extremity, positioned to engage a complementary notch in an arm 17 of a suitable locking member B, pivoted to an extension 10^a of the base, and provided with a second arm 18. The two arms 17 and 18 diverge so that the locking member B is of approximately V-shape. A spring 19 has one end anchored to the base extension 10^a and its other end connected with the arm 15 of lever L, so that the tension of said spring will normally tend to move the arm 14 to the alarm-released position, i. e. out of engagement with the trip arm 13.

Pivotedly secured to the base extension 10^a is a trigger 20 having one arm positioned to engage the arm 18 of the locking member. Said trigger member is provided with a flat extension 21 positioned to be engaged by one end of a thermally controlled actuator member C. Said member C preferably consists of a tube 22 of any suitable material, such as glass for instance, having its ends enlarged to form bulbs 23, 23^a respectively, the first mentioned bulb constituting a reservoir. Said tube is filled with a suitable liquid 24, which is capable of expanding under increase of temperature, so that it will fill the space between the two bulbs, and in fact will overflow into the bulb 23^a. The tube 18 is pivoted to the base extension 10^a as indicated at 25, the pivot point being nearer to the bulb 23 than to the bulb 23^a, so that under normal conditions with the temperature below the maximum at which the device is to operate, the material 24 while normally resting in the bulb 23, will retain the tube 18 in the position indicated in full lines in Figure 1.

In practice, the actuator member C is moved to the full line position illustrated in

Figure 1, and is retained in said position by the weight of the expansible fluid 24, as long as the bulk of said fluid is within the bulb 23. To set the device the lever L is swung 5 on its pivot to the "alarm-stopped" position, i. e. until its arm 14 engages and raises the trip arm 13, thereby locking the alarm train against movement. The lever L is then locked by placing the lug 16 in the notch of 10 the arm 17 of the lock B, the spring 19 tending to move said lever in a direction to release the trip arm 13 upon disengagement of the lock 17. Assuming an emergency condition such as a fire, the bursting of a steam 15 pipe, or the like, by which the temperature in the vicinity of the actuator member C rises beyond a predetermined maximum degree, the heat will cause the material 24 to expand and rise in the tube 18 until it finally overflows into the bulb 23^a, whereupon the 20 weight of the material 24 in said bulb 23^a added to the weight of the tube on that side of its pivot, will overbalance the weight of the reservoir end, causing the actuator C to 25 move to the dotted line position illustrated in Figure 1. The bulb 23 during its upward movement strikes the flattened plate 21 of the trigger 20, which causes the trigger in turn to engage the arm 18 of the lock B, and 30 to move said lock out of engagement with the lower end of the lever L. The instant the lever L is released, the spring 19 swings the lower end of said lever to the right, as viewed in Figure 1, thereby releasing the trip arm 13, and setting in operation the alarm train A, causing the striker 12 to hammer against the gong 11, thereby sounding a vigorous alarm. In order to reset the device, it 35 is only necessary to cool the actuator C sufficiently to cause the thermally responsive material to return to the reservoir 23, whereupon said device may be again tilted to the position illustrated in full lines, Figure 1. By then moving the lever L into engagement 40 with the trip lever 13, and with the lock member B, the parts are reset for a future emergency.

The advantages of the invention will be 45 readily understood by those skilled in the art to which it belongs. For instance, an important advantage is that a very simple form of alarm device has been provided which will remain normally inert until an abnormal temperature occurs in the space in which the 50 device is located, but which is capable of giving a very vigorous audible signal the instant the temperature reaches a predetermined maximum. Another important advantage is that a very simple form of thermally responsive element is provided, and one 55 which will quickly and promptly respond to the conditions which it is desired to control.

Having thus explained the nature of the 60 invention and described an operative manner of constructing and using the same, al-

though without attempting to set forth all of the forms in which it may be made, or all of the forms of its use, what is claimed is:

1. In an alarm of the character described, 70 a hollow actuator provided with an expansible fluid therein, means for movably supporting said actuator so that it will move from a predetermined position by expansion of said fluid, an alarm control lever, means connected with said lever for normally moving it 75 to and retaining it in a predetermined alarm-released position, means positioned to engage said lever while it is in an alarm-stopped position, so as to retain it in the last mentioned position, said retaining means being operative independently of any position assumed by the actuator, and means positioned to be engaged and moved by said actuator during movement thereof for positively disengaging said lever from its releasing means, 80 so that it is free for movement to its alarm-released position.

2. In an alarm of the character described, 85 a hollow actuator provided with an expansible fluid therein, means for pivotally supporting the actuator so that it will be rocked on its pivotal support by change of center of gravity due to expansion of said fluid, a pivotally supported control lever, means positioned to engage said lever near one end 90 while it is in a predetermined alarm-stopped position, said lever and said engaging means being so constructed and arranged as to normally retain the lever in said predetermined position, its other end being adapted to directly engage the trip arm of an alarm mechanism, means normally acting to move said control lever from said predetermined position 95 so as to release said trip arm, means for moving said lever retaining means out of 100 engagement with the lever, said last mentioned means being positioned in the line of travel of said actuator, so as to be positively moved thereby to release the control lever for free movement to alarm-released position. 110

3. In an alarm of the character described, 115 a hollow actuator provided with an expansible fluid therein, means for movably supporting said actuator so that it will move from a predetermined position by expansion of said fluid, a pivotally supported control lever, locking means for said lever positioned to engage one end of the lever while the lever is in a predetermined alarm-stopped position, said lever and said locking means being 120 so constructed and arranged as to normally retain the control lever in said predetermined position, the other end of said control lever having an offset portion adapted to directly engage the trip arm of an alarm mechanism, means normally acting to move the control lever from said predetermined position so as to release said trip arm, and means for moving said locking means out of engagement with the lever so as to free the same, 130

said lock disengaging means being positioned in the line of travel of said actuator so as to be positively moved thereby to free the lever for movement to alarm-released position.

4. In an alarm of the character described, a hollow actuator provided with an expansible fluid therein, means for movably supporting said actuator, so that it will move from a predetermined position by expansion of said fluid, a pivotally supported alarm control lever, a pivoted lock member positioned to engage one end of said control lever while the lever is in a predetermined alarm-stopped position, said control lever and said lock lever being so constructed and arranged as to normally retain the control lever in said predetermined position, the other end of the control lever being adapted to directly engage the trip arm of an alarm mechanism, means normally acting to move the control lever from said predetermined position so as to release said trip arm, means for moving said lock lever out of engagement with the control lever, said last mentioned means being positioned in the line of travel of said actuator so as to be positively moved thereby to free the control lever for movement to alarm-released position.

5. In an alarm of the character described, a hollow actuator provided with an expansible fluid therein, means for pivotally supporting said actuator so that it will be rocked on its pivotal support by change of the center of gravity due to expansion of said liquid, a pivotally supported control lever, locking means positioned to engage one end of said lever while it is in a predetermined alarm-stopped position, said control lever and said locking means being so constructed and arranged as to normally retain the control lever in said predetermined position, the other end of said control lever being adapted to directly engage the trip arm of an alarm mechanism, a spring normally acting to move the control lever from said predetermined position so as to release said trip arm, and a pivoted trigger member for disengaging the locking means from said control lever, said trigger member being positioned in the line of travel of said actuator so as to be positively moved thereby to release the lever for movement to alarm-released position under the influence of said spring.

6. In an alarm of the character described, a movably mounted actuator having an expansible fluid therein, so that it will be moved by expansion of said fluid, a pivotally supported control lever provided with an offset arm at one end adapted to directly engage the trip arm of an alarm mechanism, a spring engaging the other end of said lever so as to move it in a predetermined alarm-released position, a movable locking member having means for engaging the last mentioned end

of said control lever, said locking member being positioned to normally retain the control lever in an alarm-stopped position against the tension of said spring, and lock releasing means positioned in the line of travel of said actuator so as to be positively moved thereby to disengage the lock member from the control lever and free said lever for movement to alarm-released position under the tension of said spring.

7. In an alarm of the character described, a movably mounted actuator having an expansible fluid therein, so that the actuator will be moved by expansion of said fluid, an alarm-control lever, a spring acting to move said lever in a predetermined direction, a V-shape locking member having one end provided with means for engaging said lever to prevent movement thereof under the tension of the spring, and means operated by movement of the actuator member for engaging the other arm of said lock to release said lever.

8. In an alarm of the character described, a movably mounted actuator having an expansible fluid therein, so that the actuator will be moved by expansion of said fluid, a pivotally supported control lever having one end adapted to directly engage the trip arm of an alarm mechanism, a spring connected to said lever and normally acting to move it to alarm-released position with the other end moved to a position to free said trip arm, a locking lever having means at one end for engaging complementary means on an adjacent end of said control lever, said locking means being positioned to retain said lever in alarm-stopped position against the tension of said spring, and means positioned to engage the other end of said lock lever to disengage it from said control lever, said disengaging means being positioned in the line of travel of said actuator so as to be positively moved thereby to release the control lever.

9. In an alarm of the character described, a movably mounted actuator having an expansible fluid therein, so that the actuator will be moved by expansion of said fluid, a pivotally supported control lever, a spring normally acting to move the control lever to a predetermined alarm-released position, a pivotally mounted locking lever having one end provided with means for engaging and holding an adjacent end of said control lever so as to prevent movement of the control lever under the tension of said spring, a pivot trigger member having one end positioned to engage the other end of the lock lever, said trigger member having a portion lying in the normal path of movement of said actuator so as to be positively moved thereby and to cause it to disengage the lock lever from the control lever and thereby free it for movement under the tension of said spring.

10. In an alarm of the character described, a movably mounted actuator having an ex-

pansible fluid therein, so that the actuator will be moved by expansion of said fluid, an alarm-control lever, a spring acting to move said lever in a predetermined direction, a V-shape
5 locking member having one end provided with means for engaging said lever, so as to prevent movement thereof under the tension of the spring, and a pivoted trigger having a portion positioned to engage the other
10 arm of said lock, said trigger having a portion lying in the path of movement of said actuator member, so as to be operated thereby.

11. The combination with a gong and a clock mechanism for actuating the same, said
15 mechanism including a trip arm, of a control-lever positioned to engage said trip arm so as to directly hold it in normally locked position, means tending to move said lever in a predetermined direction to disengage the
20 lever from said control arm, means positioned to engage said lever while in an alarm-stopped position so as to hold it in the last mentioned position, a movably mounted actuator having an expansible fluid therein, so
25 that the actuator will be moved by expansion of said fluid, and means operated by said actuator for releasing said lever from its locking means.

30 In testimony whereof I have hereunto set
my hand.

ALBERT KOENIG.
